[57] CLAIM

The ornamental design for a game masterboard for selecting numbers, as shown and described.

DESCRIPTION

FIG. 1 is a perspective view of the game masterboard for selecting numbers showing my new design;
 FIG. 2 is a top plan view thereof;
 FIG. 3 is a front elevational view thereof;
 FIG. 4 is a right side elevational view thereof;
 FIG. 5 is a left side elevational view thereof;
 FIG. 6 is a bottom plan view thereof;
 FIG. 7 is a front elevational view of an alternate embodiment of FIG. 1; and,
 FIG. 8 is a perspective view of FIG. 7.
 The undisclosed rear views are unornamented.
